ington, N. J., a corporation of New JerseyApplication October 26, 1950, Serial No. 192,166
In Great Britain December 17, 1949

8 Claims. (Cl. 12—38)

1

This invention relates to apparatus for applying pressure to shoe bottoms and is illustrated as embodied in apparatus for use in attaching soles by cement to shoe bottoms, although it will be understood that the invention is not thus limited in its application.

It is an object of the invention to provide improved apparatus for applying pressure to shoe bottoms which is of simple construction and is particularly useful in the cement attachment of rubber soles and the like to shoe bottoms irrespective of the bottom contour of the shoe.

To this end and in accordance with a feature of the invention the apparatus comprises a box adapted to be filled with water or other suitable liquid, the top wall of the box being in the form of a diaphragm, providing a normally flat work engaging surface but having a depending fold which will permit upward displacement of the diaphragm where necessary during the pressure applying operation to insure the application of substantially uniform pressure throughout the bottom of the shoe. The fold is so located that if a sole is attached to the bottom of a shoe to which a heel has been previously attached, that portion of the diaphragm underlying the shank portion of the shoe will be forced upwardly by forces transmitted through the water when pressure is applied to force the shoe against the diaphragm.

The end portions of the pad are supported by soft resilient members which may be in the form of blocks of sponge rubber or like material. In accordance with a further feature of the invention that block which is adapted to underlie the forepart of a shoe has its heelward end tapered upwardly from the bottom of the box so that it may be forced downwardly causing the transmission of pressure through the liquid to that portion of the diaphragm underlying the shank portion of the shoe and permitting the forepart supporting block more readily to conform to the forepart of the shoe.

To prevent undue upward displacement of the diaphragm outwardly of the sides of the shoe and in accordance with another feature of the invention the diaphragm in these locations is clamped against upward displacement by suitably formed rubber blocks engageable with the top surface of the diaphragm.

The above and other features of the invention including various details of construction and novel combinations of parts will now be described by reference to the drawing and pointed out in the claims.

In the drawing:

Fig. 1 is a plan view of one form of pad box embodying the invention;

Fig. 2 is a plan view of the underside of the diaphragm forming the top of the pad box, this figure also illustrating the blocks associated with the diaphragm;

Fig. 3 is a section on the line III—III of Fig. 1;

Fig. 4 is a section of a portion of the apparatus along the line III—III of Fig. 1, showing the position of the parts when no work is on the pad box; and

Fig. 5 is a section on the line V—V of Fig. 1.

The apparatus comprises a box or receptacle 10 provided with a filler pipe 12 on one side thereof through which water or other suitable liquid is poured into the box. This pipe is normally closed by a plug 16. The top wall of the box has an outwardly extending flange 18 against which is clamped a rubber diaphragm 20, a clamping member 22 being provided for this purpose, the clamping member being fastened by nuts and bolts 24 to the flange 18 of the box 10.

Attached to the underside of the diaphragm 20 is a block 26 preferably formed of sponge rubber and shaped in plan as shown in Fig. 2, this block being fitted into one end of the box 10 and being of substantially the same depth as that of the box. The block has wing portions 28 and a central portion 30 the bottom of the central portion being tapered on the underside so that it is normally spaced from the bottom of the box, as shown in Fig. 3. This permits the portion 30 of the block 26 to be depressed when a shoe is pressed against the diaphragm in applying pressure to a shoe bottom as will appear as the description proceeds.

Also attached to the underside of the diaphragm 20 is a block 32 arranged to underlie the heel end of a shoe, the box being provided with an upwardly extending flange 34 for positioning the block 32 in the end of the box 10.

The diaphragm 20 is formed with a fold of material 36 extending transversely of the pad box and which when no pressure is applied thereto lies on the underside of the diaphragm in the box as shown in Fig. 4 so that the diaphragm forms a substantially flat work supporting surface. The folded portion 36 of the diaphragm is sealed at its ends 38 to prevent the escape of water from the interior of the box.

Upon applying pressure to a shoe placed on the pad box, downward movement of the portion 30 of the block 26 will cause displacement of water therefrom forcing the diaphragm upwardly

into the shank portion of the shoe as illustrated in Fig. 3. The folded portion 36 is normally substantially circular in shape to insure an easy rolling action of the fold as it rises out of its concealed position, the circular shape minimizing any initial resistance to upward movement. Regardless of the bottom characteristic of the shoe the pressure will be substantially equally distributed by appropriate displacement of the fluid in the box forcing the diaphragm upwardly as required.

To prevent the diaphragm from being forced upwardly and outwardly of the marginal portions of the shoe, blocks 40 of rubber or other suitable material may be clamped against the upper surface of the diaphragm. These blocks are of any suitable shape but are shown as being substantially semicircular in plan and sloping upwardly toward the outer portions of the pad as shown in Fig. 5. Metal clamping bars 42 held in place by screws 44 are provided for securing these blocks in position. Also, if desired, a suitable mask plate may be mounted over the toe end of the diaphragm particularly when the pad box is to be used for operating upon the bottoms of shoes of small size. The pad box is provided with two pairs of outwardly extending trunnions 46, 48 (Fig. 1), by which the pad box may be mounted in a suitable form of pressure applying apparatus in either of two positions.

The particular form of apparatus in which the pad box is mounted forms no part of the present invention and is not illustrated herein but it will be understood that preferably the apparatus will include heel and toe abutments 50, 52 and means for relatively moving the heel and toe abutments as a unit and the pad box toward and away from each other.

In the operation of the apparatus a shoe to which an outsole is to be attached is placed on the pad and the shoe may have a flat bottom or may be provided with a heel as illustrated in Fig. 4 in which case the breast of the heel is placed over the fold as illustrated. Irrespective of whether or not the shoe bottom is flat, substantially equal pressure will be exerted throughout the shoe bottom by the transmission of fluid pressure in the pressure-applying operation and the diaphragm is so constructed with the circularly shaped fold 36 that it offers no appreciable resistance to moving upwardly into the shank portion of a shoe having a heel thereon, as shown in Fig. 3. It will be apparent that, if the shoe has a heel thereon, the pad will also exert pressure against the breast of the heel. It will thus be seen that the pad box although being of very simple construction may be used equally well in operating upon flat bottom shoes or shoes with heels, the breasts of which may be vertical or not.

Having thus described my invention what I claim as new and desire to secure by Letters Patent of the United States is:

1. Apparatus for use in applying pressure to shoe bottoms comprising a box arranged to be filled with liquid, and a flexible diaphragm forming the top wall of said box, said diaphragm normally providing a substantially flat shoe bottom-engaging surface but including a transversely extending depending fold of material permitting, in response to pressure of a shoe on the diaphragm, conformation of the diaphragm to the bottom of the shoe.

2. Apparatus for use in applying pressure to shoe bottoms comprising a box arranged to be filled with liquid, a flexible diaphragm forming

the top wall of said box, said diaphragm normally providing a substantially flat shoe bottom-engaging surface but including a transversely extending depending fold of material permitting, in response to the pressure of a shoe on the diaphragm, conformation of the diaphragm to the bottom of the shoe, and soft resilient blocks supporting the toe and heel ends of the diaphragm and resting on the bottom of the box.

3. Apparatus for use in applying pressure to shoe bottoms comprising a box arranged to be filled with liquid, and a flexible diaphragm forming the top wall of said box, said diaphragm normally providing a substantially flat shoe bottom-engaging surface but including a transversely extending depending fold of material permitting, in response to the pressure of a shoe on the diaphragm, conformation of the diaphragm to the bottom of the shoe, said fold normally being substantially circular in shape.

4. Apparatus for use in applying pressure to shoe bottoms comprising a box arranged to be filled with liquid, and a flexible diaphragm forming the top wall of said box, said diaphragm normally providing a substantially flat shoe bottom-engaging surface but including a transversely extending depending fold of material permitting, in response to the pressure of a shoe on the diaphragm, conformation of the diaphragm to the bottom of the shoe, a soft resilient block supporting the toe end of said diaphragm, the heelward end of said block tapering upwardly from the bottom of the box to provide a space for liquid therebelow.

5. Apparatus for use in applying pressure to shoe bottoms comprising a box arranged to be filled with liquid, a flexible diaphragm forming the top wall of said box, said diaphragm normally providing a substantially flat shoe bottom-engaging surface but including a transversely extending depending fold of material permitting, in response to the pressure of a shoe on the diaphragm, conformation of the diaphragm to the bottom of the shoe, and a soft resilient block supporting the heel end of the diaphragm and extending toewardly substantially to said fold.

6. Apparatus for use in applying pressure to shoe bottoms comprising a box arranged to be filled with liquid, a flexible diaphragm forming the top wall of said box, said diaphragm normally providing a substantially flat shoe bottom-engaging surface but including a transversely extending depending fold of material permitting, in response to the pressure of a shoe on the diaphragm, conformation of the diaphragm to the bottom of the shoe, and rubber blocks supporting the heel and toe ends of said diaphragm, the toe-supporting block tapering upwardly from the bottom of the box toward the heel end thereof, the heel supporting block extending toewardly substantially to said fold.

7. Apparatus for use in applying pressure to shoe bottoms comprising a box arranged to be filled with liquid, a flexible diaphragm forming the top wall of said box, said diaphragm normally providing a substantially flat surface for supporting a shoe but including a transversely extending depending fold of material permitting conformation of the diaphragm to the bottom of a shoe in response to the pressure of the shoe on the diaphragm, a resilient block for supporting the toe end of said diaphragm, a resilient block for supporting the heel end of said diaphragm, the fold in said diaphragm being located adjacent to said heel end supporting block, and means

engageable with the upper surface of the diaphragm for preventing upward displacement thereof along the sides of a shoe being operated upon outwardly thereof.

8. Apparatus for use in applying pressure to shoe bottoms comprising a box arranged to be filled with liquid, a rubber diaphragm forming the top wall of said box, said diaphragm normally providing a substantially flat surface for supporting a shoe but including a transversely extending depending fold of material permitting conformation of the diaphragm to the bottom of a shoe in response to the pressure of the shoe on the diaphragm, a rubber block for supporting

the toe end of said diaphragm, a rubber block for supporting the heel end of said diaphragm, the fold in said diaphragm being located adjacent to said heel end supporting block, and means engageable with the upper surface of the diaphragm for preventing upward displacement thereof along the sides of a shoe being operated upon outwardly thereof, said last named means comprising a pair of tapered rubber blocks clamped against the upper surface of the diaphragm at opposite sides thereof.
